(57) **CLAIM**

The ornamental design for furniture for audio/video components, as shown and described.

DESCRIPTION

FIG. 1 is a perspective view of a first embodiment of an ornamental design for furniture for audio/video components showing our new design;

FIG. 2 is a front elevational view thereof;

FIG. 3 is a top view thereof;

FIG. 4 is a right side view thereof, the left side view being a mirror image thereof;

FIG. 5 is a front view of a second embodiment of an ornamental design for furniture for audio/video components showing our new design, which is identical to the first embodiment except that the front and side surfaces of the doors on the front of the lower cabinet are covered with fabric; and,

FIG. 6 is a front view of a third embodiment of an ornamental design for furniture for audio/video components showing our new design, which is identical to the first embodiment except that the doors on the front of the lower cabinet are opaque.

The broken lines shown in FIGS. 1–6 are included for the purpose of illustrating environmental elements only and form no part of the claimed design. The thickness of the large curved panel and thickness of the top surface of the cabinet form no part of the claimed design.
